US00D986863S

(12) **United States Design Patent** (10) **Patent No.:** **US D986,863 S**
(45) **Date of Patent:** ** *May 23, 2023

(54) **MOBILE PHONE**

(71) Applicant: **LG ELECTRONICS INC.**, Seoul (KR)

(72) Inventors: **Seunghyun Ji**, Seoul (KR); **Hongkyu Park**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **29/752,602**

(22) Filed: **Sep. 28, 2020**

(30) **Foreign Application Priority Data**

Apr. 2, 2020 (KR) 30-2020-0014781

(51) **LOC (14) Cl.** **14-03**

(52) **U.S. Cl.**

USPC **D14/248**

(58) **Field of Classification Search**

USPC .... D14/138 AA, 138 AB, 138 AC, 138 AD, D14/138 C, 138 R, 138 G, 203.4, 214, D14/248, 250, 315-318, 330, 341, 342, D14/345-347, 426; D21/330

CPC G06F 1/1652; G06F 1/1641; G06F 1/1647; H04M 1/0268

(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a back perspective view thereof.

The broken lines depict portions of the mobile phone that form no part of the claimed design. The dash-dot broken lines define the bounds of the claimed design and form no part thereof.

1 Claim, 8 Drawing Sheets
